FIG. 1.

Inventor -
Robert McKay,
By John Calvert, Atty.

UNITED STATES PATENT OFFICE.

ROBERT MCKAY, OF NEWLANDS, GLASGOW, SCOTLAND.

DEVICE FOR SETTING UP FORMS FOR CONTENTS-BILLS, POSTERS, AND THE LIKE.

1,370,982.

Specification of Letters Patent.

Patented Mar. 8, 1921.

Application filed February 2, 1921. Serial No. 441,866.

To all whom it may concern:

Be it known that I, ROBERT MCKAY, a subject of the King of the United Kingdom of Great Britain and Ireland, and residing at Newlands, Glasgow, Scotland, have invented a certain new and useful Improvement in Devices for Setting Up Forms for Contents - Bills, Posters, and the like, of which the following is a specification.

10 The subject of this invention is a device for setting up forms for contents bills, posters and the like for stereotype work in rotary or flatbed printing machines.

15 The invention is illustrated in the accompanying drawing in which Figure 1 is a plan, Fig. 2 a section on the line B—B of Fig. 1 and Fig. 3 a section on the line A—A of Fig. 1.

20 As shown, the device is constituted by a bed plate 1 which is originally type-high but which, except for end strips 2 and side strips 3, is cut away for the depth of one pica. Formed on the bed plate 1 in the space bounded by the strips, are grooves 4 which are parallel to the strips 2 and are

5 formed with plates the soles of which are 30 formed with ridges 6 to mate with the grooves 4 in the bed plate 1.

It will be seen that the lettered plates may be readily applied to the bed plate in correct position without any trouble in setting up.

I claim:—

25 A device for setting up forms for contents bills, posters and the like, comprising a bed-plate which is type-high but which, 40 except for end strips and side strips, is cut away for the depth of one pica, the cut away portion of said bed plate being formed with grooves parallel to certain of said strips and each one pica in depth and one pica in 45 width, said grooves spaced apart the distance of one pica, and letters formed on plates the soles of which are formed with ridges to mate with said grooves.

In testimony whereof I have signed my 50 name to this specification in the presence of two subscribing witnesses.

ROBERT MCKAY.

Witnesses:

ISABEL ROLLO,
FLORENCE HOUSTON.
